TERMINAL PLATE ASSEMBLY FIXTURE

James Oscar Van Winkle, Omaha, Nebr., assignor
to Western Electric Company, Incorporated,
New York, N. Y., a corporation of New York

Application April 30, 1945, Serial No. 591,032

5 Claims. (Cl. 29—203)

1

This invention relates to assembling apparatus and more particularly to an apparatus for assembling electrical terminals in an insulator terminal plate.

An object of the invention is to provide a simple and efficient device for rapidly assembling terminals in a terminal plate and automatically ejecting the assembly into a receiving tray.

Other objects of the invention will become apparent from the following description and the accompanying drawing, wherein:

Fig. 1 is a front elevational view of a preferred form of the invention;

Fig. 2 is a plan view of the assembly fixture shown in Fig. 1;

Fig. 3 is an end view of the assembly fixture; and

Fig. 4 is a perspective view of the terminals and terminal plate assembled by the fixture shown in Figs. 1, 2, and 3.

Referring now to the drawing wherein like reference numerals indicate the same parts throughout the several views, 10 designates a frame or base formed in the shape of a sled (Fig. 3) with its left hand end 11 turned up at an angle. Mounted on the inclined end 11 is an annular anvil or assembly block 12 having four spaced alignment pins 13 secured therein.

In the center of the anvil is a cone shaped opening 14 in which is reciprocably mounted a cone shaped ejector 15 having a threaded shank 16. This threaded shank extends through an opening in the top of the inclined end 11. Threaded on the shank 16 is a nut 17 which serves by gravity to normally retain the cone shaped ejector 15 in its lowermost position and which by adjustment determines the distance the ejecting member may be moved upwardly.

Journalized on the top of the base 10 is a swingable hammer 20 having a metal head 21. The left hand end of the hammer (Figs. 1 and 2) has an arcuate portion 22. Secured to and running through the center of this arcuate portion 22 is a shaft 23 which has its ends journalized in two side members 24. The two members 24 are secured to the sides of the base or frame 10 by locating studs 25 and screws 26.

Coiled about a part of the shaft 23 supporting the hammer is a spring 27 which has one of its ends fastened to the top of the frame 10 by a

2

screw 28; the other end of the spring being bent at a right angle to pass through an aperture 29 in the handle portion of the hammer 20. This coil spring 27 is tensioned in a counterclockwise direction to normally retain the hammer 20 in the position shown in Figs. 1 and 2.

An annular groove 30 is provided in the arcuate portion 22 of the hammer to receive a cable 31, one end of which passes through an opening in the hammer handle and is knotted thereunder as indicated at 32 in Fig. 1. The other end of the cable 31 passes down through a slot 33 (Fig. 2) and is fastened to a pivoted foot treadle 34 (Fig. 1). Thus by stepping on the foot treadle to move the cable 31 the hammer 20 is swung against the tension of coil spring 27 to strike the hammer head 21 against the anvil 12.

Mounted beneath the top and between the sides of the sled shaped base or frame 10 is a lever 37 which is pivoted on a horizontal rod 38 mounted and held in place in the frame 10 by cotter pins 39. Secured to the left hand end of the lever 37 is a disk 40 which is adapted to strike and operate the ejector 15. The right hand end of the lever 37 is bent up to be engaged by the under side of the hammer 20 when it rebounds to normal position under the recoil of spring 27.

The terminal plate with electrical terminals assembled by the above described fixture is shown in Fig. 4 of the drawing.

In performing the assembly operation, four hollow metal terminals 42 are placed on the four alignment pins 13 which hold the terminals in place and locate them with their open sides facing the center of the assembly. The operator then places the terminal insulator plate 43 with its four holes 44 coinciding with the positioned terminals 42. After which the foot treadle 34 is operated to pull the cable 31 downwardly to swing the hammer counterclockwise (Fig. 1) against the tension of coil spring 27. The hammer head 21 strikes the insulator plate 43 and forces it down over the terminals 42 to secure the parts into a unitary assembly.

As the hammer strikes it tightens the spring 27 around the shaft 23 and creates sufficient retractile force to rotate the hammer clockwise to hit the upturned right hand end of the pivoted lever 37. The blow on this end of the pivoted lever 37 causes the left hand end thereof

to move its disk 40 upward to strike the ejector 15 with such force that the terminal plate assembly of Fig. 4 is driven from the anvil through the air into a receiving tray or storage bin (not shown). The angle at which the anvil 12 is arranged determines the path of travel of the assembled parts through the air.

The base 10 of the assembly fixture may be fastened to a work bench by passing bolts through four openings 45 in the base and the foot treadle 34 may be secured to the floor by any suitable means.

It is to be understood that although a single embodiment of the invention is shown and described, the invention is not limited to that embodiment but is capable of modification and substitution of parts and general reorganization within the scope of the appended claims.

What is claimed is:

1. An assembly fixture comprising a frame, an anvil mounted in the frame, a plurality of alignment pins secured in the anvil for holding a plurality of parts in a predetermined arrangement, a hammer means pivoted in the frame, means for moving the hammer means from normal position through an arc about its pivot to engage and assemble the parts together in a unitary assembly, an ejector for ejecting the assembly, a lever for striking the ejector and having a portion in the path of the returning movement of said hammer means, and means for recoiling the hammer means to normal to hit said portion to transmit the force of said recoil through said lever to move the ejector.

2. An assembly fixture for assembling parts, comprising a base, an anvil mounted in the base at a predetermined angle and having a central aperture therein, alignment members on the anvil for holding a plurality of parts in a predetermined arrangement, a hammer pivoted in the base for assembling the parts into a unitary assembly, a spring for returning the hammer to normal position, an adjustable ejector positioned in the central aperture in the anvil, a lever pivoted in the base for operating the ejector, and means for operating the hammer to assemble the parts, whereby the spring returns the hammer to normal to strike the pivoted lever to operate the ejector to eject the assembled parts through the air in a predetermined path as determined by the angle at which the anvil is set.

3. An assembly fixture comprising a frame, an anvil mounted in the frame for holding a plurality of parts in a predetermined arrangement, a hammer means pivoted in the frame, means for moving the hammer means from normal po-

sition through an arc about its pivot to engage and assemble the parts together in a unitary assembly, an ejector for ejecting the assembly, a lever for striking the ejector and having a portion in the path of the returning movement of said hammer means, and means for recoiling the hammer means to normal to hit said portion to transmit the force of said recoil through said lever to the ejector.

4. An assembly fixture comprising a frame, an anvil mounted in the frame at a predetermined angle for holding a plurality of parts in a predetermined arrangement, a hammer means pivoted in the frame, means for moving the hammer means from normal position through an arc about its pivot to engage and assemble the parts together in a unitary assembly, an ejector for ejecting the assembly from the anvil, a lever for striking the ejector and having a portion in the path of the returning movement of said hammer means, and means for recoiling the hammer means to normal to hit said part to transmit the force of said recoil through said lever to the ejector, whereby said assembled parts are ejected from the fixture through a predetermined trajectory as determined by the angle at which the anvil is mounted in the frame.

5. An assembly fixture comprising a frame, an anvil mounted in the frame, a plurality of alignment pins secured in the anvil for holding a plurality of parts in a predetermined arrangement, a hammer means pivoted in the frame, means for moving the hammer means from normal position through an arc about its pivot to engage and assemble the parts together in a unitary assembly, an ejector for ejecting the assembly, a lever for striking the ejector and having a portion in the path of the returning movement of said hammer means, means for recoiling the hammer means to normal to hit said portion to transmit the force of said recoil through said lever to move the ejector, and adjustable means for stopping the movement of said ejector.
